UNITED STATES PATENT OFFICE

EDWARD M. MILLER, OF KENT, OHIO, ASSIGNOR TO J. B. MILLER KEYLESS LOCK COMPANY, OF KENT, OHIO, A CORPORATION

KEYLESS LOCK

Application filed July 12, 1929. Serial No. 377,812.

This invention relates to keyless locks having a permutation mechanism for causing unlocking of the same wherein the unlocking action sets the mechanism of the lock to be locked upon closing of the shackle member.

This mode of operation is highly desirable since if the lock is merely closed, and the owner thereof, through negligence or otherwise, should fail to turn the knob, any unauthorized person who should happen to pull on the lock, would open the same.

The object of my invention, therefore, is to devise a mechanism which will cause the locking member that engages the shackle to move into locked position incident to opening of the lock. When a lock wherein my novel mechanism has been incorporated, is properly operated to unlock the same, opening of the lock causes the locking member thereof to move into locked position, and subsequent closing of the shackle causes the same to be locked. If it is desired to open the lock again, it will be necessary to turn the operating member in the proper directions and the proper distances just the same as if the operating member had been moved to lock the lock.

To be more specific, I employ a locking member which is constantly urged to a locked position by means of a spring. An actuating arm is moved by a cammed member into engagement with the locking member to move it into unlocked position against the action of the aforesaid spring. One end of the actuating arm is pivoted to the shackle of the lock at a point removed from the pivotal point of the shackle with respect to the casing of the lock. The locking member having been moved to unlocking position, it is then possible to move the shackle out of the casing to unlock the lock. Movement of the shackle about its pivotal point will cause a substantially lateral movement of the actuating arm, whereupon the same will move off the cam and the locking member will be restored to its locked position by the action of the spring. If the shackle is then moved back into the casing, it will be held there by the locking member.

It can thus be seen that by using my novel

mechanism, it is impossible to leave a lock of the keyless type in a closed position without locking the same.

Further and more detailed objects and advantages of my invention will appear as the description thereof proceeds.

For a full and more complete understanding of the invention, reference may be had to the following description and accompanying drawings, in which:—

Figure 1 is a side view of the inside of a lock made in accordance with my invention.

Figure 2 is a view similar to Figure 1, showing the shackle released from the casing and the locking member in locked position, the dotted lines showing the shackle in locked position.

Figure 3 is a detailed perspective view of the locking member and spring associated therewith.

Figure 4 is a detailed perspective view of the shackle and actuating arm associated therewith.

Figure 5 is a side view of the other half of the casing and parts associated therewith.

While a preferred, specific embodiment of my invention is herein shown, it is to be understood that I am not to be limited to the exact construction illustrated and described, because various modifications of the same may be employed in putting the invention into practice within the purview of the appended claims.

In the present instance my invention is shown associated with the well known keyless lock comprising a casing which includes the members 1 and 2. A rotatable member 3 mounted on the casing member 1 has various cam surfaces affixed thereto for the operation of the lock as is well understood. The usual spring 4 is associated with the casing 1 and cooperates with notches 5 in the rotatable member 3. The spring 6 engages the end of a shackle 7 to hold the same in its open and closed positions.

The shackle 7 is substantially U-shaped and is pivoted to the members 1 and 2 as shown at 8. The other end of the shackle 7 is formed with a hook member denoted 9. An actuating arm 10 is pivoted to the shackle

7 at 11, which point is removed from the pivotal point 8. The opposite end of the arm 10 is formed with a projection 12 and has a pin 13 secured thereto for cooperation with 5 the cams on the member 3.

A locking member 14 comprises a flat quadrant shaped portion having flanges 15 and 16 on two of its sides. The locking member 14 is pivoted to the casing member 1 at 17. The 10 flange 16 has a portion 18 upraised therefrom and receives one end of a spiral coil spring 19, the other end of which abuts the casing of the lock.

The lower end of the flange 15 engages the 15 hook 9 of the shackle 7 under influence of the spring 19 and the projection 12 of the arm 10 is adapted to engage the under side of flange 16 upon proper operation of the rotatable member 3 to move the flange 15 out of engagement with the hook 9. Two spring members 20 and 21 secured to the casing member 2 at 22 are adapted to bear against the arm 10 and spring 4 respectively when the parts are assembled.

25 The operation of the lock is as follows:— The member 3 is rotated back and forth a certain number of times and for a certain distance, according to the manner in which the cams thereon were placed so that the cam denoted 23 engages the pin 13, moving the arm 10 which causes the projection 12 to rotate the locking member 14 in a clock-wise direction against the action of the spring 19. This 30 position of the parts is shown in Figure 1 and the shackle may now be moved from the casing. When the shackle is moved from the casing it pivots about the point 8 as previously set forth, which action causes the arm 10 to move in a substantially horizontal direction. This horizontal movement of the arm 10 brings the pin 13 out of engagement with the cam 23, whereupon the spring 19 which 35 has been compressed, will now expand, rotating the locking member in an anti-clockwise direction, whereupon it will assume a position as shown in Figure 2. If the shackle is now moved in the position shown in dotted lines in Figure 2, hook 9 will once again be engaged by the lower extremity of the flange 40 15, thereby locking the lock.

It can thus be seen that it is impossible to close the shackle of my novel lock without locking the same. Having once moved the shackle to its closed position, it is once again necessary to turn the rotatable member 3 through the proper combination before the shackle can again be opened.

Having thus described my invention, what I claim as new and desire to secure by Letters 55 Patent of the United States, is:—

1. In a lock of the class described, the combination of a casing, a shackle pivoted thereto near one of its ends, the other end being movable in and out of the casing, means for locking 60 the movable end of the shackle in the

casing, and mechanism for moving said locking means to unlocked position, said mechanism including an arm pivoted to the shackle at a point removed from the pivotal mounting of the shackle on the casing, said arm 70 being operable upon movement of the shackle to allow the locking means to move to locked position.

2. In a lock of the class described, a casing, a shackle movable in and out of the casing, a locking member, an actuating means therefor, a cam for moving the actuating means into engagement with the locking member to move the same to unlocked position, and mechanism associated with the shackle and actuating means and operable incident to movement of the shackle for moving the actuating means away from the cam to allow the locking member to move to locking position.

3. In a lock of the class described, a casing, a shackle movably mounted in said casing, a locking member, an arm movably mounted on the shackle for actuating the locking means, a manually operable rotary means for operating the movable arm to cause release of the locking means, said shackle being operable to shift the movable arm upon unlocking action and to cause said locking means to subsequently become effective to lock the shackle, when the shackle is moved to closed position.

4. In a lock of the class described, a casing, a shackle pivoted to said casing and movable to locking and unlocking position, a locking means for retaining the shackle in locked position, an actuating arm for the locking means, said arm being pivoted to the shackle and shiftable incident to opening and closing movement thereof, actuating means for causing said arm to move the locking means into unlocking position, said actuating means being rendered ineffective to permit the locking means to become effective upon shifting of the arm incident to the opening movement of the shackle.

5. In a lock of the class described, a casing, a shackle movably mounted on the casing, a locking means for the shackle, a movable arm pivoted to the shackle and adapted to be moved thereby, a rotary member for actuating the arm to cause release of the locking means, said arm being movable by the shackle upon opening movement to cause the engagement thereof with the rotary member, to permit the locking means to become effective to lock the shackle upon closing movement thereof.

In testimony whereof I affix my signature.
EDWARD M. MILLER.
